(57) **CLAIM**

I claim the ornamental design for a bowed mug drinking vessel with tabbed lid, substantially as shown and described.

DESCRIPTION

The present invention relates to the aesthetic features of a vessel for containing fluids or other material.

FIG. 1 is a perspective view of a bowed mug drinking vessel with tabbed lid showing my new design;

FIG. 2 is a left side elevation view thereof;

FIG. 3 is a right side elevation view thereof;

FIG. 4 is a back side elevation view thereof;

FIG. 5 is a top plan view thereof;

FIG. 6 is a front side elevation view thereof;

FIG. 7 is a bottom plan view thereof;

FIG. 8 is a perspective view of a bowed mug drinking vessel with tabbed lid showing a second embodiment of my new design;

FIG. 9 is a left side elevation view of the vessel of FIG. 8;

FIG. 10 is a right side elevation view of the vessel of FIG. 8;

FIG. 11 is a back side elevation view of the vessel of FIG. 8;

FIG. 12 is a top plan view of the vessel of FIG. 8;

FIG. 13 is a front side elevation view of the vessel of FIG. 8; and,

FIG. 14 is a bottom plan view of the vessel of FIG. 8.

The broken lines in the drawings are for illustrative purposes only and form no part of the claimed design.
